HUSKING HOOK

Harold J. Kelly, Des Moines, Iowa

Application June 22, 1937, Serial No. 149,687

2 Claims. (Cl. 130—4)

My invention relates to husking hooks used in husking corn.

More particularly it is my object to provide a husking hook of very simple, durable and inexpensive construction which has what I may for convenience call a two-way hook with a hook projecting upwardly in the direction of the arm (which is of regular and ordinary construction), which hook also has a hook projecting across the palm of the hand and away from the thumb (when the hook is installed).

Another object is to provide a hook of the kind under consideration mounted so as to be located just above the base of the ball of the thumb when in use.

The advantages of this two-way hook will appear below.

With these and other objects in view, my invention consists in the construction, arrangement and combination of the various parts of my husking hook, whereby the objects contemplated are attained, as hereinafter more fully set forth, pointed out in my claims, and illustrated in the accompanying drawing, in which:

Figure 1 is a front elevation of a hook embodying my invention; and

Figure 2 is a rear elevation of the same.

In the drawing herewith I have shown at 10 a leather wrist band intended to fit over the front of the wrist and upper part of the hand and thumb. For convenience I have shown the hand in dotted lines indicated at 11 in Figure 1.

Secured to the upper part of the wrist band 10, at the top thereof, is a strap 13 and a buckle 35 14 for fastening the upper part of the wrist band snugly around the wrist.

My hook is formed preferably integrally as a part of a metal plate 15. The plate is riveted to the front of the wrist band 10 and has a curved finger 16 extending away to where it will be slightly beyond the second knuckle of the thumb when in use. At the extreme end of the finger 16 is a strap slot 17.

At the lower part of the plate 15, at what would be substantially the base of the thumb, a hook member 18 is formed by bending the material of the plate away from the portion which fits against the hand and then upwardly toward the wrist portion, as indicated in Figure 1. This is, broadly speaking, a general structure, although it is located closer to the thumb than are most husking hooks.

My hook, however, has a second hook member or pointed portion 19 projecting from the main hook 18, substantially parallel with the plate 15,

and in a direction to be away from the thumb when the hook is on the hand.

Thus when the hook is on the hand for use, the hook 18 will be pointed in the general direction of the wrist, and the hook member 19 will be 5 pointed generally away from the thumb, as shown in Figure 1.

Secured to the plate 15, at the place that will be over the center of the palm when the device is in use, is a second strap 20 intended to extend 16 around the thumb of the hand and which is then threaded through the slot 17 and extended around the back of the wrist and fastened to a buckle 21 on the plate 10.

In Figure 1 the hook is shown placed on the 15 hand in position for use. For convenience I call it a two-way husking hook.

My two-way husking hook is superior to other husking hooks in use, because it makes it possible to more conveniently and quickly make 20 openings through the husks on small ears of corn (and ears located in certain positions).

I believe the use and advantages of my two-way husking hook will be clear after I refer briefly to the ordinary method of husking.

For husking by a right handed person, my hook can, of course, be used in the ordinary way.

In the ordinary husking process, the ear is caught by the left hand approximately in the 30 center, with the thumb toward the small or silk end of the ear. Almost all huskers wear cotton work gloves.

The two-way husking hook is strapped on the right hand, and the next operation involves 35 drawing the hook 18 across the opposite side of the ear, loosening the husk and removing them on that side.

Third, the left hand, with the original hold it had on the ear, gathers the remaining loosened 40 husks and holds them while the right hand breaks the ear from the stalk.

This is known as the one-two-three motion and is the procedure used with great speed by champions, who husk as many as thirty to forty 45 ears per minute.

This procedure works satisfactorily for large and medium size ears located so they can be properly grasped by the left hand in the manner suggested.

But for small ears and nubbins, or for ears lying on the ground, or for ears hanging in the wrong position on the stalk, I have found that my hook 19 can be used with great convenience.

With the ordinary one-way husking hook it is 55

- almost impossible to make the opening through the husk on small ears or nubbins, and it is very inconvenient to husk ears that lie in certain positions with relation to the husker. In ordinary husking of small ears, the hook catches in the left hand mitten near the finger tips as the ear is so small that it is hard to grasp it in the left hand and insert the hook in the husk without catching the material of the mitten.
- 10 My two-way husking hook will loosen the husk on the ears of any size and on ears in any position without extra effort on the part of the husker, and without the necessity for using any other device. Many huskers use a husking peg
- 15 in addition to the husking hook in order to take care of small ears.

Where the ear is too small to conveniently use the hook 18, the method employed is as follows:

Instead of grasping the small ear with the left hand in the ordinary way as above explained, it is caught between the thumb and fingers of the left hand, next to the small end, and then the right hand is shoved across the ear away from the husker, using the hook 19 above the thumb of the left hand. The motion of the right hand is away from the left hand mitten instead of toward it, and the husk can be loosened without interference with the mitten on the left hand. Then the left hand removes and holds the husks 30 in the same manner as has been heretofore explained, while the ear is being broken from the stalk by the right hand. This mode of operation cannot be followed with other husking hooks.

Sometimes also ears hang on the stalk so as 35 to be pointing directly toward the person doing the husking. In that case, instead of rather awkwardly turning the hand to catch the ear in the standard fashion, this ear may be caught by the left hand with the thumb toward the butt of the ear. The right hand is then shoved 40 down on the opposite side from the left hand, using the hook 19 to loosen the husk, after which the regular procedure is followed to finish the husking of that ear.

45 Also there are always some ears lying on the

ground. They do not have to be caught in the standard fashion because they are loose from the stalk. The husker picks them up in the easiest way and uses which ever one of the hooks 18 or 19 is most convenient. After the ear is grasped in the ordinary way, it is husked in the manner first above explained. If the ear should be grasped with the thumb toward the butt, then the hook 19 is used as heretofore explained.

It is probably a fact that the advantages which 10 have been mentioned here are hard to appreciate without actually using the two-way hook in the field.

I claim as my invention:

1. In a device of the kind described, a flexible 15 wrist band adapted to cover a portion of the wrist and front upper palm of the hand of the user, means for fastening the wrist band on the wrist, a plate secured to the wrist band having a hook-like portion with a sharp point, bent 20 away from the lower edge of the plate, and then upwardly substantially parallel with the plate where it will be approximately above the ball of the thumb of the wearer, said hook member having a second sharpened hook member in substantially the same plane as the first hook member 25 projecting at a right angle to the first hook member and away from the thumb of the wearer substantially parallel with the plate, and a holding strap connected to the plate and adapted to be extended under the thumb.

2. In a device of the class described, a plate, means for holding the plate adjacent the ball of the thumb of a wearer, said plate having a hook-like portion formed from the material of the 35 plate bent away from the plate and thence parallel therewith, so that it will point toward the wrist of the wearer when installed, said hook-like portion having a sharpened pointed projection in the same plane as the hook-like portion 40 extending at a right angle to the hook-like portion so as to be parallel with the palm of the hand and point away from the thumb when the device is in use.
